UNITED STATES PATENT OFFICE.

HORACE B. SEVERANCE, OF LANSING, MICHIGAN.

DESIGN FOR A HOOP-LUG.

SPECIFICATION forming part of Design No. 26,202, dated October 20, 1896.

Application filed June 8, 1896. Serial No. 594,798. Term of patent 7 years.

To all whom it may concern:

Be it known that I, HORACE B. SEVERANCE, of Lansing, in the county of Ingham and State of Michigan, have invented and produced a new and original Design for Hoop-Lugs, of which the following is a specification, reference being had to the accompanying drawing, showing a part thereof.

The present figure is a perspective view of the hoop-lug, showing my design.

The leading feature of my design consists in a curved bulge which terminates at each end in a plate, said plates having holes for screws, by means of which the lug may be secured in the place or position desired.

A is the main portion of the lug, which is circular in its general contour, and B B are the plates. These are flat and are ordinarily at about right angles to the curved bulge A.

What I claim is—

The design for a hoop-lug substantially as described and shown.

In testimony whereof I affix my signature in the presence of two witnesses.

HORACE B. SEVERANCE.

Witnesses:

J. H. MOORES,
J. A. DEAN.
